(57) CLAIM

The ornamental design for a chair, as shown and described.

DESCRIPTION

FIG. 1 is a top perspective view of my new design for a chair.
FIG. 2 is a front side elevation view of FIG. 1.

FIG. 3 is a back side elevation view of FIG. 1.

FIG. 4 is a right side elevation view of FIG. 1.

FIG. 5 is a left side elevation view of FIG. 1.

FIG. 6 is top plan view of FIG. 1; and,

FIG. 7 is a bottom plan view of FIG. 1.

The irregular broken lines in all figures indicate environmental matter and form no part of the claimed design.
